[57] ABSTRACT

A flat cooling box for capsules disk-cells is disclosed consisting of two round cooling pots at both sides of a flat connecting piece, provided with concentric annular grooves for cooling fluid and current supply. Inflow and outflow channels are directed through the center of the circle with symmetrical passages in communication with the annular grooves. The cooling pots are connected with their connecting piece through annular riveting.

COOLING BOX FOR INSTALLATION IN STACKS OF DISK-CELLS

BACKGROUND OF THE INVENTION

1. Field of the Invention

This invention is concerned with a cooling box for installation in stacks of disk-cells and consists of two round cooling pots having their flat heat-transmitting surfaces at both sides of a platelike connector hermetically joined thereto, for connecting the device to cooling-fluid connectors and current connectors, in which the connecting piece has inflow and outflow channels directed from its edge to its interior, with each having its outlet in a passage perpendicular thereto and going through the wall-thickness of the connecting piece, with which the fluid-distributors of the two cooling pots are in communication.

2. Description of the Prior Art

A known cooling box of this type (German Exhibited Text DT-OS 1,914,790) has a substantially rectangular connecting plate, which carries the two cooling pots. These cooling pots have relatively wide and thick flanges at their periphery, which serve to fasten them to the connecting piece. The part of the cooling pots projecting above the connecting piece is used as a current-connection. In the interior of the cooling pots a fluid-distributor is located. This distributor is formed of a number of webs, which are connected to each other by means of a central and an eccentric passage so that a great pressure-drop prevails in the interior of the cooling pot and, moreover, the heat-exchange area is limited.

This special type of web arrangement, however, requires special machining, so that such cooling pots can not be made on automatic lathes. Further the shape of the connecting piece requires more material.

SUMMARY OF THE INVENTION

The fundamental problem solved by the invention is to save material and simplify manufacture while making a cooling box having a relatively large heat-exchanger surface over which the cooling fluid flows and a relatively smaller pressure drop to thus diminish the heat buildup in the cooling box.

In accordance with the invention the solution of the problem posed is achieved by using a connecting piece having a round plate with inflow and outflow channels directed through and aligned with the center of the circle, and having passages disposed symmetrically of the center of the circle. Further it carries axial rim-projections on both sides which by annular riveting are brought into engagement with radial projections from the cooling pots. The cooling pots have in their interior, concentric, continuous, annular channels that extend to the faces and are in communication with the passages.

In order to avoid destruction of the stacked disk-cells (thyristor plates), which are held together by the action of external forces and are liable to breakage through inevitable irregularities of the clamping device, it is advantageous if the flat heat-transfer surfaces of the cooling pot, which extend against the adjacent disk-cells, are formed as annular surfaces extending from the outer rim of the cooling pot to the middle zone and are offset from one another.

The annular surfaces and the annular channels permit the manufacture of the cooling pots on automatic

lathes. The connecting piece can also be produced from bar material in automatic lathes, needing only a subsequent machining in boring machines.

BRIEF DESCRIPTION OF THE DRAWINGS

The drawings illustrate one embodiment for carrying out the features of my invention, which are explained in more detail in the following and in which:

FIG. 1 illustrates a side view of a cooling box, a portion of which is illustrated as a cross sectional view;

FIG. 2 illustrates a plan view of a connecting piece;

FIG. 3 illustrates a cross sectional view of a cooling pot; and

FIG. 4 illustrates a plan view of the device of FIG. 1.

DESCRIPTION OF THE PREFERRED EMBODIMENT

The cooling box, which is held at both sides in electric contact with adjacent disk-cells (not shown), consists of a central round connecting piece 1 having parallel faces 6 and 7, carrying axial rim-projections 6a and 7a, by which, through annular riveting, it is connected with the two round cooling pots 8 and 9. The fluid-tight arrangement is obtained by conventional seal-rings inserted in annular grooves in the cooling pots. The round connecting piece 1 has two inflow and outflow channels 2 and 3, directed to, and aligned with, the center of the circle, and into which are screwed the connector-pieces 2a and 3a. Passages 4 and 5 are provided symmetrical to the center of the circle, and, perpendicular to the inflow and outflow channels 2 and 3. The passages 4 and 5 thereupon pass through the wall thickness of the connecting piece. In the interior of the cooling pots 8 and 9 are continuous concentric annular channels 10, which extend to the faces 6 and 7 of the connecting piece, and are connected to the passages 4 and 5. Thus two similar paths of coolant flow are achieved from one passage through the annular channels to the other passage, that is, there is a symmetrical division of the cooling fluid, making possible improved flow conditions with less pressure-drop. Together with this increased optimum heat-exchange area in the interior of the cooling box, greatly diminished heat resistance is also obtained so that instead of water as coolant, electrical insulating fluids having lower heat-dissipation can be used. These fluids may be necessary, particularly in the case of hightension equipment.

Each cooling pot 8 and 9 has annular surfaces 8b and 9b protruding from the rim and middle zone. In the event of tilting of the contact surfaces, these surfaces keep the mechanical bending stress on the sensitive thyristor disks so small that breakage of the disk is avoided. The electrical and thermal transfer resistance is hereby scarcely impaired. At two screw-threaded inserts 11 and 12 at the rim of the connecting piece 1, a current-connector 13 can be screwed on, making it possible to have a series and/or parallel hook-up of the disk-cells.

In the foregoing, the invention has been described in reference to specific exemplary embodiments. It will be evident, however, that variations and modifications as well as the substitution of equivalent constructions and arrangements for those shown for illustration, may be made without departing from the broader scope and spirit of the invention as set forth in the appended

claims. The specification and drawings are accordingly to be regarded in an illustrative rather than in a restrictive sense.

What is claimed is:

1. A cooling box for installation in stacks of disk-cells comprising,

two circular disk-shaped cooling pots having flat internal heat transmitting surfaces;

a disk-shaped coolant and electrical connector joined to the flat heat transmitting surfaces of the cooling pots, the connector having an inlet and an outlet channel aligned with one another and passing from the outer circumference of the connector, towards the center of the disk each of said channels being connected to an internal passage within the connector, each of the passages being substantial perpendicular to the inlet and outlet channels;

axial rim projections on both sides of the connector;

radial projections on the cooling pots, said projections being secured to the axial rim projections of the connector to form an hermetic seal between the connectors and the pots; and

the cooling pots having continuous concentric circular channels therein, the center of which is the center of the disk, said circular channels connecting the internal inlet and outlet passages of the connector to provide coolant distribution within the cooling pots.

2. A cooling box for installation in stacks of disk-cells as in claim 1 wherein two current connecting fittings are connected to the connector for permitting the connection of current to the connector.

3. A cooling box for installation in stacks of diskcells as in claim 2 wherein the flat heat transmitting surface of the cooling pot is a round surface set back from the outer rim and extending into the interior of the pot.

4. A cooling box for installation in stacks of diskcells as in claim 3 wherein the cooling pot is formed of machined annular channels and round heat transmitting surface.

5. A cooling box for installation in stacks for diskcells as in claim 1 wherein the axial rim projections and the radial projections on the cooling pots are joined by annular riveting.
